UNITED STATES PATENT OFFICE.

CLIO B. YAW, OF ARLINGTON, NEW JERSEY, ASSIGNOR, BY MESNE ASSIGNMENTS, TO
REMINGTON TYPEWRITER COMPANY, OF ILION, NEW YORK, A CORPORATION OF
NEW YORK.

TYPE-WRITING MACHINE.

1,142,005.

Specification of Letters Patent. Patented June 8, 1915.

Application filed February 5, 1913. Serial No. 746,305.

To all whom it may concern:

Be it known that I, Cléo B. Yaw, citizen of the United States, and resident of Arlington, in the county of Hudson and State 5 of New Jersey, have invented certain new and useful Improvements in Type-Writing Machines, of which the following is a specification.

My invention relates to tally strip mechanism for typewriting machines and its general object is to provide improved mechanism of the character specified.

More specifically stated, one object of the invention is to provide a tally strip mechanism which is especially adapted for "listing" purposes.

Another object is to provide a tally strip mechanism equipped to handle two tally strips, one of which is retained for a record 20 as is common and the other of which is adapted to be severed at frequent intervals.

Another object is so to equip a typewriting machine with a tally strip mechanism that said machine is adapted both for general typewriting work, such as correspondence, the making out of bills, etc., and is also adapted to be used for listing purposes providing both a series of lists and a record of such lists.

Another object is to associate counting or indicating devices with a tally strip mechanism so that the number of entries on the tally strip or strips may be automatically indicated.

Another object is to provide a divided or sectional platen, one section of which is adapted for ordinary commercial typewriting and the other for tally strip or listing purposes.

Another object is to provide for controlling from a single line spacing mechanism the sections of a divided platen so as to enable the sections to be separately actuated at will or to be actuated together concurrently 45 so that the full length of the platen may be made use of in connection with a wide work sheet.

Other specific objects will hereinafter appear.

To the above ends my invention consists in the features of construction, combinations of devices and arrangements of parts herein-after described and particularly pointed out in the claims.

In carrying out my invention in the pres-

ent instance, I have shown it applied to a No. 11 Remington typewriting machine but the nature of the invention is such that it may be readily adapted in whole or in part to other styles of writing machines. Two 60 co-axial platens or platen sections or parts are provided, each having its own line spacing ratchet wheel and a co-operative pawl, and both being associated with feed roller mechanism. The pawls are controlled from 65 the regular line spacing handle or lever and may be adjusted with respect to each other and to their ratchet wheels so that either or both may operate at will when the line space lever is actuated. A tally delivery 70 carrier or roll holder and a tally receiving carrier are mounted above the right-hand or tally platen or section on a support or bracket which is secured to the platen carriage near the right-hand end thereof. The 75 tally receiving roll holder being positively connected to the tally platen by a train of gears, said roll holder is adapted to receive the innermost of two tally strips which are delivered from the delivery roll holder together with a carbon strip. The outer of the two tally strips is preferably torn off 80 at intervals against the upper edge of the paper apron which is serrated for the purpose. The construction leaves the left-hand 85 or main platen section practically free and unencumbered so that it may be used for ordinary typewriting work independently of the tally platen and devices. A spring mounted indicating dial or disk is also provided associated with a stationary pointer and disconnectibly connected by gearing with the tally receiving roll so as to be turned one step for each actuation of said roll, thus indicating the number of items 90 written thereon. When an individual list is completed the pointer and indicator will show the number of items on said list, which number may be printed prior to tearing off the written section of the outer tally strip. 95 Thereafter the dial is disconnected so that its spring may turn it back automatically to normal position prior to the next indicating operation.

My invention will be explained more in 105 detail in connection with the accompanying drawings which illustrate one form of my invention and wherein—

Figure 1 is a fragmentary front elevation of the upper part of a Remington typewrit- 110

ing machine embodying my invention. Fig. 2 is a fragmentary side elevation of the same, partly in section. Fig. 3 is a face view of a portion of a listing or tally strip. Fig. 4 is a longitudinal sectional view of the platen. Figs. 5 and 6 are longitudinal sectional views respectively of the tally delivery and receiving roll holders or carriers. Figs. 7 and 8 are fragmentary side elevations of the line spacing mechanism, the parts being shown set in different relationships in the two figures. Fig. 9 is a sectional view taken on a plane indicated by the dotted line α in Fig. 8 and looking in the direction of the arrow at said line. Fig. 10 is a rear elevation partly in section of the tally indicating mechanism and its mounting.

As appears from Figs. 1 and 2 the main frame of the machine comprises posts 1 supporting a top plate 2 from which rise standards 3 secured whereto are grooved guide rails 4 coöperating through anti-friction balls 5 with the front bar 6 and rear bar 7 of a truck which further includes end bars 8 connecting the front and rear bars. With said truck is shiftably connected through arms 9 the end bars or plates 10 of a platen frame which further includes cross bars or rods 11, 12 and 13 connecting said end bars, 20 said frame and truck constituting a carriage. The end plates 10 provide bearings for stub shafts 14 to the outer ends of which are secured finger wheels 15. The shafts 14 support a two-part or divided platen, the 25 construction whereof is fully illustrated in Fig. 4. The main or longer part, element or section of the platen is designated as a whole by the numeral 16 and is arranged coaxially with and at the left of the supplementary 30 part or tally platen designated as a whole by 17. These elements, sections or parts 16 and 17 may be considered as platens in themselves. The main platen 16 comprises a hollow core 18 of wood and an outer sheath 19 of rubber. Secured to the left end of the core 18 as by wood screws 20 is a platen 40 head 21 having an outwardly extending hub 22 and a short inwardly extending hub 23. The hub 22 is made fast by a set screw 24 45 to the left-hand stub shaft 14. Arranged within the hollow of the core 18 and frictionally engaging therewith and extending rightwardly outside of and beyond the same is a tube or supporting device 25 which at 50 its left-hand end fits over the hub 23. Ears 26 turned inward from the left-hand end portion of the tube 25 abut against the inner face of the hub 23 and are secured to the platen head 21 by screws 27 passing through said hub. Thus the tube 25 is fixed to the platen 16. At its right-hand end the sleeve 25 fits over the inwardly extending hub 28 55 of a ratchet wheel 29, the sleeve having ears 30 turned from its end portion, which ears 35 are secured fixedly to the hub 28 by screws

31. The ratchet wheel 29 is provided with peripheral ratchet teeth 32 which coöperate with pawl mechanism hereinafter described. A short hub 33 extends rightward from the ratchet wheel and the right-hand stub shaft 70 34 which passes through an opening bored through this hub, and extending through the body of the ratchet wheel and through the hub portion 28, is secured in fixed relation to the ratchet wheel as by a cross pin 75 34. Thus the ratchet wheel 29 and right-hand finger wheel 15 are rigidly connected through the tube 25 with the platen 16, and rotary motion communicated either to said ratchet wheel or said finger wheel will be transmitted through said tube to said platen. The right-hand shaft 14 bears in a bushing 35 which has an enlarged threaded portion 36 that screws into an opening in the right-hand end plate 10 of the platen frame. A 80 locking nut 37 threaded on the portion 36 and outside the end plate 10 is maintained in the bushing 35 in fixed relationship with said end plate. The bushing is counter-bored at its inner end to receive the hub 33. 85 The tally platen 17 is mounted rotatably on the right-hand portion of the tube 25 and is arranged between the platen 16 and its ratchet wheel 29. Said platen 17 comprises a metal tube or core 38 having a sheath or 90 covering 39 of rubber equal in diameter to the sheath 19. The platen 17 is provided at its ends with heads 40 and 41 which are suitably secured to the tube 38 and bear rotatably on the tube 25. The head 40 is a 95 disk made fast as by soldering to the tube 38 and of substantially equal diameter to the sheaths 39 and 19. The disk abuts both sheaths and with them provides a substantially continuous surface from one end of 100 the divided platen to the other. The right-hand platen head 41 has a groove in its inner face in which the tube 38 fits and is secured as by soldering. The head 41 is provided with peripheral gear teeth 42 for connecting 110 it with the tally receiving holder or spool as will be hereinafter described. The head 41 is provided with a rightward extension 43 which may bear on a shouldered portion of the ratchet wheel 29. The extension 43 is 115 provided with peripheral ratchet teeth 44 corresponding with the ratchet teeth 32. The ratchet teeth 44 coöperate with line spacing mechanism for the platen 17 and thus in effect the head 41 is a line spacing 120 ratchet wheel.

Hand controlled pawl devices are provided for coöperating with the ratchet wheels 29 and 41, said devices being adjustable or settable so that an operation of a single 125 finger piece may be effective to line space the platen 16 or the platen 17, each independently of the other, or to line space both platens together as one. Said devices are illustrated in Figs. 1, 2, and 7 to 9 and com- 130

prise an arm 45 having a hub portion 46 which is mounted loosely on the enlargement 36 to the left of the end plate 10, said enlargement being smoothed down at this point 5 to provide a suitable bearing surface. Mounted at the upper end of the arm 45 is a headed shouldered screw 47 which is secured in place on the arm by a locking nut 48. The screw provides a support for a collar 10 49 provided with a flange 50. Mounted rotatably on the collar 49 is an angular pawl member or actuator 51 provided with a lateral pin 52 which engages a comparatively large hole 53 in the arm 45, thus providing 15 for limited relative movement between the pawl member and its supporting arm. Said pawl member extends forward and downward and at its lower end terminates in a pawl tooth 54 which is adapted to coöperate 20 with the ratchet teeth 32 to turn the platen 16, though normally separated from said tooth. The pawl member 51 has an extension 51^a above its pivot, said extension being provided at its upper edge with a series or set of notches 25 55, 56 and 57 for coöperation with a plunger device presently to be described, which is mounted on a second pawl member or actuator 58, the latter being pivotally supported on the shouldered portion of the screw 47 30 and confined between the head thereof and the flange 50 of the collar 49, said flange serving as a spacing device to maintain the pawl members or line space actuators 58 and 51 properly spaced apart and in the 35 planes of their respective ratchet teeth 44 and 32. The pawl member 58 extends downward from its pivot and terminates in a tooth 59 which is adapted to coöperate with the ratchet teeth 44 to turn the platen 17. 40 The pawl member 58 has an extension 58^a above its pivot, said extension being angularly disposed to the tooth carrying portion below the pivot and extending substantially parallel with the extension 51^a. The extension 58^a terminates in a rightwardly bent lip or ledge 58^b which overlies the extension 51^a. Supported on the extension 58^a is a socket piece 60 which fits into a hole in the lip 58^b, a shoulder 61 on said socket piece 50 resting on the top of the lip, the lower end of the socket piece being spread or upset as indicated at 62. The construction is such that the socket piece is firmly fixed on the lip 58^b and is in effect a part of the pawl member 58. The socket piece extends above the lip 58^b and is cylindrical in cross section, being bored out as indicated at 63 to provide a socket or depression which receives a plunger 64, the lower end whereof is formed into 55 a tooth 65 adapted to coöperate with the notches 55 to 57, thus providing interlocking devices for maintaining the actuators or pawl members 51 and 58 set in varying normal relationships. The plunger is provided 60 with a stem 66 which extends upward through a hole in the top of the socket piece and is screwed into a cap 67 which fits over and loosely embraces the upper portion of the socket piece. The cap is knurled and provides a convenient finger piece for manipulating 70 the plunger. A spring 68, coiled around the stem 66 and confined between the plunger and the upper end of the socket piece, tends constantly to press the plunger downward and maintain its tooth 65 in engagement with one of the notches aforesaid. By pulling up on the finger piece 67 the spring 75 68 may be overcome and the plunger tooth disengaged from the pawl member 51, enabling a relative adjustment of the pawl 80 members or line space actuators 51 and 58 to take place by turning the pawl member 58 on its pivotal axis. Then when the plunger is released it may engage with another 85 of the notches at the top of the pawl member 51. When the plunger is engaged with one of the notches it will be understood that the two pawl members are connected to turn on their common pivotal axis as a single 90 member or device.

In order to actuate the pawl members, manual devices are provided which are like those found in the Remington machine and comprise a link 69 pivotally connected at its rear end at 70 to the pawl member 51, said 95 link extending forward and being connected at its front end at 71 to the longer arm of a bell crank 72 pivoted at 73 to the carriage truck. The shorter arm of said bell crank is pivotally connected by a link 74 to a crank 100 arm 75 secured by a screw 76 to the rear end of a rock shaft 77, said rock shaft bearing in a housing 78 mounted on the right-hand end of the carriage truck. A spring 79 arranged in a depression in the housing surrounds and is connected to the rock shaft and tends to maintain the connected parts normally in the position shown in Fig. 2. Forward of the housing the rock shaft terminates in a handle or finger piece 80 which 105 is curved downward so that it may be convenient to the hand of the operator. A line space regulator of the ordinary Remington construction is provided comprising an arm 81 having an eye 82 which fits over the nut 110 83. The arm 81 is adjustably secured to the outer face of the right-hand end plate 10 by a screw 83 which coöperates with a slot 84 in the arm. By loosening the screw the arm may be set at desired positions on the end plate. The upper end of the arm is provided with a set of notches 85 with which 115 coöperates the tooth 86 of a spring mounted plunger similar in construction to the plunger mechanism above described in connection with the plunger 64, said tooth 86 being connected to and controlled by a finger piece 87 which fits over the top of a socket piece 88. Said socket piece is secured to a lip 89 turned laterally outward from the upper 120 and 125 an 130

arm 90, said arm being loosely and rotatably mounted on the enlargement 36 and being confined between the end plate 10 and the arm 45. The left-hand end of the enlargement 36 is threaded and receives a nut 91 which loosely confines the arms 45 and 90 on the smooth bearing portion of the enlargement 36. The arm 90 is provided with a lateral pin or stop 90^a which lies in the path of and in front of the arm 45 and serves normally as a stop therefor as shown in Figs. 1 and 2. Of course, the normal position of this stop 90^a may be varied by resetting the plunger tooth 86 with respect to the notches 85, thus varying the normal position of the arm 45 and providing for a line spacing advance movement of the pawl 51 and the ratchet wheel engaged thereby to an extent corresponding with one, two or three units of line space distance as determined by the spacing of the teeth of the line space ratchet wheel. The pawl tooth 86 is shown in its middle position or engaged with the middle notch 85 and so as to provide for a line space advance amounting to two units. The ratchet teeth 32 are engaged by a roller detent 92 mounted on a spring arm 93 which is secured by a screw 94 to the under side of a lug 10^a on the extreme rear portion of the right-hand end plate 10, said detent maintaining the ratchet teeth and connected parts in adjusted positions.

The paper feeding devices comprise a paper deflector or apron 95 which is curved around the under side of the two platens and extends continuously substantially throughout their length. As will be understood from Figs. 1 and 2 main and secondary feed rollers numbered respectively 96 and 97 are provided, the same coöperating with the platens through openings in the deflector. The feed rollers for the two platens are mounted on separate sets of supports or hangers but are releasable together by operating a single release key. The upper forward edge of the deflector 95 is serrated opposite the right-hand platen or section 17 as indicated at 98 to provide a cutting device.

The tally strip mechanism proper is mounted on a supporting frame comprising upright end plates or arms 99 and 100 and a connecting cross bar 101 which is bifurcated at its ends, the bifurcations receiving headed screws 102 which pass through the end arms and positively secure said arms and said cross bar together, making a single rigid frame or support. This support is mounted on the cross rod 12 of the platen frame, the arms 99 and 100 being perforated so that the rod may pass through them, and the arm 100 being provided with a hub 103 which fits over the rod and receives a set screw 104 which coöperates with said rod to secure the supporting frame rigidly on the platen

frame. This supporting frame is arranged near the right-hand end of the rod 12 and so that the tally holders supported on said frame may be above the tally platen 17. The delivery roll holder or tally supply spool 70 designated as a whole by the numeral 105 is mounted at the top of the supporting frame on a shaft 106 and comprises as best shown in Fig. 5 a hollow tube or core 107 surrounding the shaft 106 and provided at its left end with a flange 108 to which is fixed a hub portion 109, the hub portion fitting inside the left end of the core 107 and being secured thereto by a screw 110. A bearing plate 111 is fixed to the outer face 75 of the flange 108 and bears on the shaft 106. The right end of the tube 107 is closed, the closed end 112 bearing on said shaft. Fixed to the end 112 as by soldering is a socket piece 113 which in turn is fixedly secured to the shaft 106 by a set screw 114. Thus the holder or carrier 105 is secured to the shaft 106 so as to turn therewith. The outer face of the piece 113 is depressed as indicated at 80 115 and receives a disk 116 of fiber or leather. The depression fits over and co-operates with the circular head 117 of a screw 118 which screws into the upper end of the arm 100 and is set thereon by a locking nut 119. The screw 118 thus provides a support 85 and bearing for the right-hand end of the holder 105 and the shaft 106. At its left-hand end the shaft 106 is depressed as indicated at 120, the depression engaging the pointed end of a bearing pin 121 (Fig. 1) 100 which is slidably mounted at the upper end of the arm 99. Outside said arm said bearing pin is provided with a flange 122 and a knurled finger portion 123. The pin is engaged in the space between said flange and said finger 105 portion by the bifurcated upper end of a leaf spring 124, the lower end of which is secured by a screw 125 to the outer face of the arm 99. This spring acting against the flange 122 tends constantly to press the pin 121 inward and maintains it engaged with the end of the shaft 106. The pressure of the spring is transmitted to the shaft with the result that the fiber disk 116 is maintained frictionally engaged with the face of 110 the screw head 117, the parts coöperating to act as a friction brake for the tally holder as it is turned. By pulling outward on the finger piece 123 the pin 121 may be disengaged from the shaft 106, allowing it and 115 the holder to be removed.

The tally receiving roll holder or carrier 120 designated as a whole by the numeral 126 is mounted below the delivery holder and as illustrated in Fig. 6 comprises a solid body 125 portion 127 which is supported on a shaft 128, the left end of said shaft being reduced and bearing in the arm 99, while the right end of said shaft bears in the arm 100 and extending outward beyond the same ter- 120 130

minates in a pinion or small gear wheel 129. The body portion 127 terminates at the left in a flange 130, the outer face of which is depressed as indicated at 131, thus providing a cup-like receptacle which receives a friction spring plate 132 which is maintained in the depression 131 by a cover or disk 133, said cover being secured to the shaft 128 by a set screw 134. The cover or disk fits in the depression 131 and is adjustable toward and from the bottom thereof so as to vary the friction exerted by the spring or friction plate 132. This plate is of ordinary construction tending to bow outward as shown in Fig. 6. It will be understood that it frictionally connects the cover 133 with the holder or carrier 127 and since this cover or device 133 is fixed to the shaft, said holder will be frictionally connected to turn with said shaft unless a restraining force sufficient to overcome the friction is exerted on it. The inner or bottom faces of the depression 131 and of the cover 133 are slightly depressed or countersunk as shown in Fig. 6, in order to insure that the friction spring 132 will coöperate with these devices effectively near their outer edges, the friction thus being applied at a considerable distance from the axis of rotation and where it will be most efficient. The periphery of the flange 130 is knurled as illustrated in Fig. 1, so that it may be employed for turning the receiving roll holder directly by hand when desired. The body portion 127 is formed with a longitudinal slot, groove or cut-out 135 in which is arranged an arm 136 pivoted at 137, and provided with a tail 138 by which the arm may be swung up out of the groove or slot 135 in which it is normally seated, said arm coöoperating with said groove to secure the end of the tally strip thereto. Fixed to the shaft 128 outside the holder proper by a cross pin 139 is a pinion 140 which meshes with a pinion 141 rotatable on the rod 12. Fixed to the pinion 141 as by soldering is a toothed detent wheel 142, said detent wheel being arranged at the right of the pinion 141. Said pinion and said detent wheel are maintained close to the inner face of the arm 100 by a collar 143 on the shaft 12. The pinion 141 meshes with the gear teeth 42 and thus positively connects the tally platen with the receiving holder or carrier. A roller detent 144 arranged at the back of the wheel 142 coöperates with the teeth thereof, said detent being mounted at the free end of a spring arm 145 which extends upward behind the arm 100 and is secured to the back thereof by screws 146. The detent devices comprising the roller 144 and the wheel 142 act through the pinion 141 on both the holder 126 and the tally platen 17, serving to prevent accidental rotation of these parts and maintain them in adjusted position.

In the present instance I prefer to employ two tally strips or work sheets one of which is for record purposes. Said sheets designated in the drawings by the numerals 147 and 148 are associated with a carbon strip 149 which is interposed between the two tally strips with its carbonized face inward or facing the inner tally strip 147. The three sheets or strips 147, 148 and 149 are wound into a roll on a tube or core piece 150 of 70 pasteboard or the like, said tube fitting over the core 107 of the delivery or supply spool and being maintained frictionally connected thereto by a bowed spring 151 (Fig. 5) which is arranged within the tube, the ends 30 of said spring abutting against the shaft 106 and its intermediate portion bowing upward through a slot 152 in the core and frictionally engaging the inner face of the tube 150. The three strips 147, 148 and 149 are drawn 85 off together at the rear of the delivery or supply roll and extend downward at the rear of and around the tally platen 17, passing over the deflector 95 and between the platen and its feed rollers. At the front of 90 the platen the outer strip 148 is left free but the other two strips 147 and 149 are wound on the receiving roll holder, being secured thereto by the locking arm 136 which is employed to force the end portions of said 95 strips down into the groove 135. Between the receiving roll holder and the platen the strips pass between a slotted bar 153 and a pivoted severing blade 154 provided with an operating finger piece 155, these parts being 100 mounted on the tally supporting frame and comprised in a paper severing mechanism that is the invention of A. W. Smith and is disclosed and claimed in his pending application, Serial No. 742,801, filed January 18, 1913. This severing mechanism is employed to cut the strips 147 and 149 at desired intervals, while the outer strip 148 is adapted to be torn off or cut against the serrated edge 98. 110

My present improvements are primarily intended for listing purposes and it frequently happens that it is desirable to record the number of items comprised in the individual lists. To this end there is associated with the tally mechanism indicating devices which are illustrated in Figs. 1, 2 and 10. The indicating devices proper comprise a coöperating dial and pointer mechanism which are mounted on a support that is pivoted to swing on the rod 13 at the rear of the tally strip mechanism in order to throw the indicating mechanism into and out of use. The swinging support comprises 115 an arm or bracket member 156 provided with a hub 157 which bears rotatably on the rod 13. The arm 156 extends upward from its hub and has a rightward extension 158 which is bored out to provide a bearing for 120 a shaft 159. The shaft projects beyond its 125 130

bearings and has suitably secured at its left-hand end a gear wheel 160 which is adapted to mesh with the pinion 129 on the shaft 128. At its opposite end the shaft 159 has 5 secured to it by a cross pin 161 a beveled pinion 162 which meshes constantly with a circular set of beveled gear teeth 163 formed at the under side of a circular plate or disk 164. Said disk is provided with a hub 165 10 which bears on a headed shouldered screw 166 that screws into a boss 167 formed at the upper side of the extension 158. The bottom of the disk 164 is supported on the boss which enables the gear 163 to clear the 15 upper face of the extension 158 and maintain said gear in proper engagement with the pinion 162. Secured to the upper face of the hub 165 by screws 168 is a circular dial plate 169, said dial plate being beneath 20 the head of the screw 166. The upper edge portion of the dial plate is thickened as indicated at 170, thus providing a raised annulus which is impressed at its upper face with a circular scale or series of indicating 25 marks 171 as shown in Fig. 1. Coöperative with this circular scale or dial 171 is a stationary pointer 172 secured by a screw 173 to an arm 174 which projects upward at the rear of the dial and terminates above the 30 pointer in a rounded finger portion 175. The arm 174 is bent under the disk 164 and has a downward extension which is secured by a screw 176 to the back of the extension 158. An arm 177 is secured by rivets 178 at 35 the rear of the arm 156 and the arm 177 extends upward at the rear of said arm 156 and is bent around the extension 158, terminating at its forward end in an upstanding portion 177^a, the upper edge of which is 40 just beneath the dial plate 169. The portion 177^a serves as a stop coöperating with a pin 179 which is fixed to and projects downward from the dial plate. The two stop devices coöperate to limit the turning movements 45 of the dial plate and are maintained normally in contact by a coiled spring 180 which is arranged between the dial plate 169 and the disk 164 and surrounds the hub 165. The inner end of said spring is made fast 50 to said hub by a screw 181 while the outer end is secured as by a screw 182 to the stop device 177^a. The spring tends constantly to turn the rotary indicating member comprising the dial plate 169, hub 165 and disk 164 55 in a direction counter to the arrow in Fig. 1. When swung back to the full line position in Fig. 2 the indicating devices are disconnected from the tally mechanism and are inoperative. Said devices are maintained in 60 this inoperative position by detent devices which comprise a ball detent 183 which coöperates with a recess or depression 184 formed in a flange 185 which may be part of the hub 157. The ball 183 is arranged in 65 a seat or depression 186 formed in the pro-

jecting portion 187 of a collar 188 secured by a screw 189 to the rod 13 at the left of the hub 157. The ball 183 is constantly pressed toward the flange 185 by a coiled spring 190 which is arranged in the depression 186 behind the ball. With the indicating mechanism swung back out of operation the ball 70 engages with the depression 184 to hold the parts set as shown in Fig. 2. To render the indicating mechanism operative the finger 75 piece 175 is pulled forward, swinging the indicating mechanism to the dotted line position in Fig. 2 and bringing the gear wheel 160 into mesh with the pinion 129. In this position the ball detent 183 coöperates with 80 a second depression 184 to hold the parts set. Preferably the teeth of said gear and pinion are sharpened or pointed so as to facilitate their engagement. The collar 188 prevents displacement of the indicating 85 mechanism along the rod 13 toward the left while toward the right such displacement is prevented by the lug 10^a.

The present invention is preferably employed in connection with a reversely operating tabulator of the character disclosed in my co-pending application, Serial No. 738,235, filed Dec. 23, 1912, and it is also desirable in some classes of listing work to employ computing mechanism such, for example, as that found in the Remington machine and known as the Wahl adding mechanism. In making use of the invention for listing or tally purposes the tally strips with the interleaved carbon strip are arranged as 90 shown in Figs. 1 and 2. The indicating devices are swung forward to the dotted line position in Fig. 2, thus connecting them with the tally mechanism and the line spacing or pawl devices are set as in Fig. 8. From 95 Fig. 8 it will be observed that the plunger tooth 65 is engaged with the notch 55 on the pawl member 51 and that consequently the pawl member 58 is set so that its lower portion is to the rear of the lower portion 110 of the pawl member 51. As a result the pawl tooth 59 is set in advance of the pawl tooth 54 so that when after each printing operation the line spacing mechanism is actuated, said pawl tooth 59 will engage with 115 its ratchet teeth 44; while the pawl tooth 54 will be held out of operation. As a consequence each actuation of the line spacing handle or lever 80 will be transmitted through the train of devices comprising the 120 rock shaft 77, crank arm 75, link 74, bell crank 72 and link 69 to the pawl member 51 and from it through the connection 55, 65, to the pawl member 58. The result will be 125 that the pawl members 51 and 58 will swing together as a single piece on the bearing screw 47 until the pawl tooth 59 engages with its ratchet teeth 44 after which the carrier 45 will begin to turn on its axis and will swing the pawl members bodily rear. 130

ward, causing the tooth 59 to turn the ratchet 44 and through it the tally platen 17 to which it is fast, said tally platen turning on its support or bearing 25, said tube or bearing, together with the main platen 16 remaining quiescent during the turning of the tally platen, being held by the roller detent 92. This turning of the tally platen advances the two tally strips from one line 10 to the next so as to space properly between the type impressions, these type impressions taking place at the front of the platen and being transmitted through the usual ribbon (not shown) to the outer tally strip 148, and 15 simultaneously through the carbon or transfer strip 149 to the inner or record tally strip 147. The tally strips are fed over the tally platen when it is turned as described by reason of the co-operation of the feed rollers 96 and 97 with said platen. The upper end of the outer tally strip 148 is free during such advance but the carbon and the record tally strip are connected to the receiving roller 126, to which roller motion is transmitted from the tally platen through the train of gears comprising 42, 141 and 140. This provides for the take-up of these sheets as they are fed upward from the platen. The frictional or yielding connection between the receiving roll and its shaft 128 through the devices comprising the friction spring 132 provides that the feeding of these strips over the platen and the simultaneous take-up thereof on the receiving roller 126 shall not be interfered with by reason of the varying diameter of the portions of the strips wound up on said roller. Although the shaft 128 is positively connected to the platen and always receives the same proportional turning movement therefrom, the roller 126 need not participate in the full extent of this movement at all times, owing to the slip joint. Each line space advance movement of the tally platen is transmitted as described to the receiving roller 126 and from said receiving roller is transmitted through the pinion 129, gear wheel 160, shaft 159, pinion 162 and gear 163 to the rotary indicating member comprising 50 the dial plate 169, this movement being counter to the spring 180 and moving the stop 179 away from the stationary stop 177^a, the guide plate turning in the direction of the arrow in Fig. 1.

55 The parts are so adjusted and proportioned that for each line space movement of the platen the scale 171 will be turned a unit distance as represented by the spaces between successive index marks on the scale, so that said marks will be brought successively into register with the pointer 172. Consequently starting initially always from the same point, the dial will register the number of line space movements that have 65 been communicated to the platen, and as one of said movements takes place after each operation of printing an item or line will also indicate the number of items that have been printed on the tally strip; or in other words, the indicating mechanism provides 70 a line counter for the tally. Assuming for example that the tally strip is being used to list the yardage in different bolts of cloth that are to constitute a shipment and that there are ten such bolts having the respective lengths indicated by the numbers in Fig. 3, then when the yardage of the last bolt has been written the point "10" on the scale 171 will be opposite the pointer 172 and the operator typewrites "10 PC" at 75 80 the side of the list, indicating 10 pieces. Also, the total amount of yardage as indicated on the adding mechanism is written as a footing to the list. Thereupon the strip 148 is torn off against the serrated edge 98 85 at a point below the footing or total. The torn off portion may be used in any desired way; for example, as a pastier on the parcel containing the bolts of cloth, in order to advise the consignee of the contents. Of course, the matter appearing on the section of the strip 148 in Fig. 3 is duplicated through the carbon on the record strip 147, and is succeeded on said record strip by other similar entries, the record strip containing them being wound on to the receiving roll holder until it is full, when the record strip is severed by the knife 154 and the rolled portion thereof removed from said roll holder. It is to be understood that 90 after each list is completed on the strip 148 the indicating mechanism is temporarily disconnected from the pinion 129, allowing the spring 180 to turn the indicating dial backward until it is arrested by the engagement of the stop 179 with the stop 177^a, after which the indicating mechanism is re-connected with the pinion 129. It is further to be understood that the tally mechanism may be employed in other ways than that 95 described and for other uses than those stated.

In order to use the main platen 16 alone for ordinary correspondence work or the like, independently of the tally platen and its associate mechanism, the line spacing pawl mechanism is set as in Fig. 7 with the plunger tooth 65 in engagement with the notch 57. This re-adjustment of the pawl members 51 and 58 sets the pawl tooth 54 in 100 advance of the pawl tooth 59 and so that while the tooth 59 is held out of operation the pawl tooth 54 will co-operate with its line spacing ratchet teeth 32 at each operation of the lever 80 to turn the main platen 16 independently of the tally platen 17, the latter being held quiescent by the detent 144 which acts on said tally platen through the toothed detent wheel 142 and connected parts. 105 110 115 120 125 130

When it is desired to write on a sheet corresponding in width to the combined lengths of the two platens or platen elements or sections 16 and 17 the operator first should remove or detach the tally supporting frame, this being readily accomplished by detaching the frame rod 12, loosening the screw 104 and removing the supporting frame and associate parts from the rod 12 which should then be replaced. Thereafter the plunger tooth 65 is reset so that it is in engagement with the central notch 56 as shown in Fig. 3. This sets the pawl members 51 and 58 so that their respective teeth 54 and 59 are at the same distance from their respective ratchet wheels so that at an actuation of the line spacing handle 80 both pawl teeth will coöperate with their ratchet wheels to turn the two platen sections simultaneously and to equal extents, the platen sections thus operating as a single unitary platen and the single wide sheet which they support, being advanced evenly throughout its entire width by the coöperation of the left-hand and right-hand sets of feed rolls 96 and 97 with their respective platen sections. Of course, instead of a single wide sheet two comparatively narrow sheets may be arranged side by side and fed together simultaneously.

Various changes may be made without departing from my invention.

What I claim as new and desire to secure by Letters Patent, is:—

35 1. In a typewriting machine, the combination of means for supporting and feeding a plurality of work sheets, line spacing devices coöperative with said means and operative by a single finger piece, and means for setting variably said line spacing devices to afford an operation of said line spacing devices to feed either of said plurality of work sheets independently of the other or both of said work sheets together at will.

45 2. In a typewriting machine, the combination of two platens, platen line spacing devices operative by a single finger piece, and means for affording adjustment of said devices to line space either platen separately as desired by an actuation of said finger piece or both of said platens simultaneously by an actuation of said finger piece.

3. In a typewriting machine, the combination of two platens, line spacing ratchet wheels one for each platen, a plurality of pawls one for each ratchet wheel, a single finger piece operative on both pawls, and pawl setting means comprising devices for setting said pawls so as to throw either one into operation and the other out of operation.

4. In a typewriting machine, the combination of two platens, line spacing ratchet wheels, one for each platen, pawls, one for each ratchet wheel, a single finger piece op-

erative on both pawls, and pawl setting means comprising devices for setting said pawls alternatively in position for operation and also comprising other devices for assisting to simultaneously render both of said pawls operatively engageable with said ratchet wheels when said finger piece is actuated whereby at will either platen alone may be rotated while the other remains stationary and whereby both platens may be caused simultaneously to rotate together.

5. In a typewriting machine, the combination of two line spacing pawl devices, and setting means mounted on said devices for varying their normal relationship to each other, said setting means moving on and with said pawl devices during line spacing actuations.

6. In a typewriting machine, the combination of two line spacing pawl devices, setting means mounted on said devices for varying their normal relationship to each other, a line spacing handle, and connections to enable said handle to actuate both of said pawl devices, said setting means moving on and with said pawl devices during line spacing actuations.

7. In a typewriting machine, the combination of two line spacing pawl devices, setting means mounted on said devices for varying their normal relationship to each other, said setting means moving on and with said pawl devices during line spacing actuations, a line spacing handle, and a train of devices connecting said handle directly to one of said pawl devices, the other of said pawl devices being operatively connected to said handle through said train of devices and said setting means.

8. In a typewriting machine, the combination of two platen elements, line spacing actuators one for each platen element, said actuators being normally operatively disconnected from their associate platen elements, and devices for interlocking said actuators in varying relationships.

9. In a typewriting machine, the combination of two platen elements, line spacing actuators one for each platen element, and devices for interlocking said actuators in varying relationships, said interlocking devices comprising a series of notches on one actuator and a spring pressed engaging device on the other.

10. In a typewriting machine, the combination of two platen elements, line spacing actuators one for each platen element, and devices for interlocking said actuators in varying relationships, said interlocking devices comprising a series of notches on one actuator, and a spring pressed plunger controllable by hand and provided with a tooth engageable at will with said notches.

11. In a typewriting machine, the combination of two line spacing pawl devices piv-

totally mounted on a common support, and setting means operative on said pawl devices for varying the normal relationship of said devices to each other.

5 12. In a typewriting machine, the combination of two line spacing pawl devices coaxially pivoted and arranged side by side, and setting means on said devices for varying their normal relationship.

10 13. In a typewriting machine, the combination of two line spacing pawl devices pivotally mounted on a common support, setting means for varying the normal relationship of said devices to each other, and hand actuated means for affording movement of said support to render said devices effective.

15 14. In a typewriting machine, the combination of two line spacing pawl devices, a finger piece, connections between said finger piece and one of said pawl devices for actuating the same from said finger piece, and means for transmitting movement from said actuated pawl device to the other pawl device, said means being adjustable to vary the 25 effect of such transmission.

20 15. In a typewriting machine, the combination of two platen elements, line spacing actuators one for each platen element, devices for setting said actuators in varying 30 normal relationships, and hand controlled means connected to one actuator for operating both actuators.

25 16. In a typewriting machine, the combination of two coaxial line spacing wheels, a member pivoted coaxially with said wheels, and two hand operated line spacing pawls pivoted on said member.

30 17. In a typewriting machine, the combination of two coaxial line spacing wheels, 40 a member pivoted coaxially with said wheels, two line spacing pawls coaxially pivoted on said member, and setting means for varying the normal relationship of said pawls with each other.

35 18. In a typewriting machine, the combination of two coaxial line spacing wheels, a member pivoted coaxially with said wheels, two hand operated line spacing pawls pivoted on said member, and devices 45 for interlocking said pawls in varying normal relationships.

40 19. In a typewriting machine, the combination of two coaxial line spacing wheels, a member pivoted coaxially with said 55 wheels, two hand operated line spacing pawls pivoted on said member, devices for interlocking said pawls in varying normal relationships, and a single finger piece for actuating said pawls.

45 20. In a typewriting machine, the combination of two coaxial platen elements, two line spacing ratchet wheels arranged side by side one for each platen element, an arm pivoted coaxially with said ratchet wheels, 50 two pawl members coaxially pivoted on

said arm, one of said members having a lost motion connection with said arm and being connected with a train of actuating devices, and means for variably setting the pawls in respect of each other.

70 21. In a typewriting machine, the combination of two coaxial platen elements, two line spacing ratchet wheels one for each platen element, an arm pivoted coaxially with said ratchet wheels, two pawl members coaxially pivoted on said arm, one of said members having a lost motion connection with said arm and being connected with a train of actuating devices, and devices for interlocking said pawls comprising a series 75 of notches on one pawl and a coöperating spring pressed plunger on the other pawl.

22. In a typewriting machine, the combination of two platen elements, two line spacing ratchet wheels one for each platen element, a pivoted arm, two pawl members pivotally supported on said arm, each being provided with a pawl tooth coöperative with one of said ratchet wheels, one of said pawl members being further provided with a 80 series of notches and the other with a coöperative spring pressed plunger, said notches and said plunger coöperating to maintain the pawls set in varying relationships, a lost motion connection between one 85 of said pawl members and said arm, a line spacing handle, and a train of devices connecting said line spacing handle with the last mentioned pawl member.

23. In a typewriting machine, the combination of two platen elements, two line spacing ratchet wheels one for each platen element, a pivoted arm, two pawl members pivotally supported on said arm, each being provided with a pawl tooth coöperative with one 90 of said ratchet wheels, one of said pawl members being further provided with a series of notches and the other with a spring 95 pressed plunger, said notches and said plunger coöperating to maintain the pawls set in varying relationships, a lost motion connection between one of said pawl members and said arm, a line spacing handle, and a train of devices connecting said line spacing handle with the last mentioned pawl member. 100

105 24. In a typewriting machine, the combination of two platen elements, a paper roll holder positively connected to one of said platen elements, line spacing devices for said platen elements controlled by a single 110 finger piece, and means for variably setting said devices so as to line space one of said platen elements while the other platen element and the paper roll holder remain 115 quiescent and so as to line space the other 120 125 130

platen element and its connected roll holder while the other platen element remains quiescent.

25. In a typewriting machine, the combination of a platen element, a second platen element, a paper supply holder and a paper receiving holder, gears connecting said receiving holder with said second platen element, separate spacing wheels for said 10 platen elements, separate pawls one for each line spacing wheel, a single line spacing handle operative on both the pawls, and means for variably setting said pawls to change their normal relationship.

15. 26. In a typewriting machine, the combination of a main platen, a tally platen, line spacing wheels one for each platen, a detent 20 coöperating with the main platen line spacing wheel, a tally supply roll holder, a tally receiving roll holder, a train of gears connecting said receiving roll holder with said tally platen, detent devices connected with said train of gears, line spacing actuators for said line spacing wheels, said actuators 25 being controlled by a single finger piece, and setting means for rendering either of said actuators effective at will.

27. In a typewriting machine, the combination of a platen, line spacing devices, indicating devices, means for rendering said indicating devices operative at certain actuations only of said line spacing devices, and other means for throwing said indicating 30 devices entirely out of the control of said line spacing devices.

28. In a typewriting machine, the combination of a platen, a rotary tally receiving holder, line indicating devices, a train of gears connecting said platen, said holder and 40 said devices, and means for separating certain elements of said train so as to disconnect said indicating devices.

29. In a typewriting machine, the combination of tally strip mechanism comprising 45 a tally receiving holder, and means for turning said holder; indicating devices for indicating the turning movements of said holder; said indicating devices comprising a spring mounted dial and a stationary 50 pointer; and connections between said dial and said holder, said connections comprising a shaft, a pinion on said holder, a gear on said shaft intermeshing with said pinion, a beveled pinion on said shaft, and a beveled 55 gear connected to said dial and meshing with said beveled pinion.

30. In a typewriting machine, the combination of tally strip mechanism comprising a tally receiving holder, and means for 60 turning said holder; indicating devices for indicating the turning movements of said holder, said indicating devices comprising a

stationary pointer, a coöperating rotary dial, stop devices for said dial, and spring means tending constantly to maintain said stop devices in engagement; and connections between said dial and said holder.

31. In a typewriting machine, the combination of tally strip advancing mechanism; and indicating devices connectible with 70 said mechanism, said devices comprising a pivoted support, a pointer stationary on said support, a coöperating dial on said support, stop devices, and spring means connected to said dial and normally maintaining said stop devices in engagement, said support being pivotally movable to connect and disconnect said indicating devices with said tally strip advancing mechanism.

32. In a typewriting machine, the combination of tally strip advancing mechanism, indicating devices connectible with said mechanism, said devices comprising a pivoted support, a pointer stationary on said support, a coöperating dial on said support, 80 stop devices, spring means connected to said dial and normally maintaining said stop devices in engagement, said support being pivotally movable to connect and disconnect said indicating devices with said tally strip advancing mechanism, and detent devices 85 coöperative with said support to maintain said indicating devices disconnected from or connected with said tally strip advancing mechanism.

33. In a typewriting machine, the combination of tally strip advancing mechanism, indicating devices connectible with said mechanism, said devices comprising a pivotally mounted supporting arm provided 100 with a hub, a pivoted arm, a pointer stationary on said arm, a coöperating dial on said support, stop devices, spring means connected to said dial and normally maintaining said stop devices in engagement, said support being pivotally movable to connect and disconnect said indicating devices with said tally strip advancing mechanism, and detent devices 105 coöperative with said arm to maintain said indicating devices disconnected from or connected with said tally strip advancing mechanism; said detent devices comprising a spring pressed ball 110 coöperative with depressions in said hub.

Signed at the borough of Manhattan, city of New York, in the county of New York, and State of New York, this 4th day of February, A. D. 1933.
